UNITED STATES PATENT OFFICE.

JAMES MORRISON, OF CINCINNATI, OHIO, ASSIGNOR TO THE HIGHLAND BODY MANUFACTURING COMPANY, OF ELMWOOD PLACE, OHIO, A CORPORATION OF OHIO.

WAGON-BODY.

1,179,739.

Specification of Letters Patent. Patented Apr. 18, 1916.

Application filed August 6, 1915. Serial No. 43,926.

To all whom it may concern:

Be it known that I, JAMES MORRISON, a citizen of the United States, and a resident of the city of Cincinnati, in the county of 5 Hamilton and State of Ohio, have invented certain new and useful Improvements in Wagon-Bodies, of which the following is a full, clear, and exact description, reference being had to the accompanying drawings, 10 forming part of this specification.

My invention relates to wagon bodies, particularly for automobiles. In such structures it is desirable to combine durability and strength with ease of erection and simplicity and inexpensiveness of parts, and it 15 is the object of my invention to provide a body and top, and certain special irons for supporting the flare board and top of the body which have the elements above set 20 forth as desirable.

It is my object to make the top easily removable and to so combine the irons for flare board and top that they may be assembled easily and secured with one set of 25 bolts.

These objects I accomplish by that certain construction and arrangement of parts to be hereinafter more specifically pointed out and claimed.

30 In the drawings, Figure 1 is a perspective view of the body and top. Fig. 2 is an end elevation of the flare board iron. Fig. 3 is a side elevation thereof, taken from the inside of the wagon body. Fig. 4 is an end 35 elevation of the flare board and top irons assembled. Fig. 5 is a side elevation of the parts shown in Fig. 4. Fig. 6 is a cross section on the line 6, 6, of Fig. 4.

The body has a bed 1, to which is hinged 40 at the back a tail gate 2. The body is extended outwardly at 3 at each side of the rear of the bed, and strut irons 4, 4, are provided, having screwthreaded ends 5, with nuts 6, and with flat upper ends 7 to lie 45 alongside of the side boards 8.

Special flare board irons 9 are provided, being flat to extend along the inside of the side boards of the wagon, and having ends passed through the bed to receive securing 50 nuts 10. These irons are pierced with apertures to receive securing bolts 11, the said

bolts being also passed through the side boards of the wagon and through the strut irons (at the rear).

The flare board irons are offset at 12 so as 55 to rest on the top of the sides, and extend outwardly from the offsets at 13 so as to support the flare boards 14, at the proper angle. Bolts 14^a are employed to secure the flare boards against these ends 13 of the 60 irons. It will be understood that there are four of these irons and two have right hand and two left hand offsets.

At the rear along the flat ends 7 of the struts are placed the plates 15, which have 65 staples 16 for securing the tail board chain 17. These plates have flanges 18 so as to seat over the lower portion of the flat ends 7 of the struts but lie flush with them at their upper end. The securing bolts 11 for 70 the struts and flare board irons also pass through these plates, so that but two bolts are required to hold all three irons.

As so far described, there has been no mention of the top or the means for mounting the same. It can be seen that a wagon body without a top has now been described complete, however, and my new body can be used in this way without the top. Moreover the top can be attached without employing any further bolts, the bolts 11 and 14^a being long enough to secure the irons for the top, and the top irons can be mounted without changing or dismounting the parts now described as forming up a topless body.

The top 20 having the four side standards 21, may be of any design desired, but it is preferred to employ the standard canopy top. The side standards are braced 90 and held to the wagon body both on the inside and the outside of the wagon. For the inside, irons 22 are provided which lie along the inside of the standards and are bent at 23 to lie along the flare boards. For 95 the outside, irons 24 are provided, to lie along the outside of the standards. The securing bolts 25 pass through both the inside and the outside braces, and firmly hold the irons to the standards. The outside iron 100 bends at 26 along the under side of the end 13 of the flare board iron, and it is

channeled so as to seat over this iron. Here again, the bolts 14^a for the flare board iron pass through the inner standard iron, the flare board and its iron and the outside iron. The outside iron depends at 27 at an angle downwardly from the bend at 26, and lies along the side boards of the wagon at the front where it is in a position to receive the upper securing bolt 11 of the flare board iron. At the rear this depending portion is channeled to seat over the top of the plate for the chain staple, where it will also receive the end of the upper securing bolt 11.

It is readily seen that to put up the top 15 it is only necessary to take the nuts off of the ends of the various bolts now described, and slip the irons for the standard of the top in place over the ends of the bolts, properly seating the channels in the case of 20 the outside irons. This operation is an easy one and can be done readily by two men who do not need to be skilled to accomplish it.

The omission of mention of equivalent 25 structures in my invention is not desired to limit the claims that follow to the exact form and structure described, when the claims do not call for it specifically.

Having thus described my invention, 30 what I claim as new and desire to secure by Letters Patent, is:—

1. In a wagon body comprising a bed, sides and flare boards, securing irons to engage the sides, with offsets to fit over the 35 top of the sides and flaring portions to engage the flare boards, top standards and inner and outer irons to hold the standards with the lower ends of these irons bent to engage the flare boards, one set also bent to 40 engage the sides, and bolts common to both the securing irons and standard irons to secure the parts together.

2. In a wagon body comprising a bed, sides and flare boards, securing irons to engage the sides with offsets to fit over the 45 top of the sides and flaring portions to engage the flare boards, top standards and inner and outer irons to hold the standards with the lower ends of these irons bent to engage the flare boards, one set also bent to 50 engage the sides, and bolts common to both the inner and outer irons and the flare of the securing irons to secure the parts together.

3. In a wagon body, in combination with a bed, and sides for the same, a flare board, an iron for securing the same, said iron secured to the wagon side, an upper portion bent to engage the top of the side, and a 55 flaring portion extending from said bent portion for mounting the flare board, and means for securing a top standard to the said parts comprising irons to engage such standard on two sides, one of said irons being bent to lie along the flare board and

the other to lie along the flaring portion of the flare board iron, for the purpose described.

4. In a wagon body, in combination with a bed, and sides for the same, a flare board, 70 an iron for securing the same, said iron secured to the wagon side, an upper portion bent to engage the top of the side, and a flaring portion extending from said bent portion for mounting the flare board, and means for securing a top standard to the 75 said parts comprising irons to engage such standard on two sides, one of said irons being bent to lie along the flare board and the other to lie along the flaring portion of the flare board iron, and being channeled to engage over said flare board iron, for the purpose described.

5. In a wagon body, in combination with a bed, and sides for the same, a flare board, 80 an iron for securing the same, said iron secured to the wagon side, an upper portion bent to engage the top of the side, and a flaring portion extending from said bent portion for mounting the flare board, and 85 means for securing a top standard to the said parts comprising irons to engage such standard on two sides, the inner one of said irons being bent to lie along the flare board and the outer one to lie along the flaring 90 portion of the flare board iron, a strut iron secured to the wagon side opposite the flare board iron, and an extension on the outer top iron to engage over said strut iron, for 95 the purpose described.

6. In a wagon body, in combination with a bed, and sides for the same, a flare board, an iron for securing the same, said iron secured to the wagon side, an upper portion bent to engage the top of the side, and a 100 flaring portion extending from said bent portion for mounting the flare board, and means for securing a top standard to the 105 said parts comprising irons to engage such standard on two sides, the inner one of said irons being bent to lie along the flare board and the outer one to lie along the flaring 110 portion of the flare board iron, and extended downwardly to lie along the side board opposite the flare board iron, for the 115 purpose described.

7. In a wagon body comprising a bed, sides and flare boards, securing irons to engage the sides, with flaring portions to engage the flare boards, top standards and inner and outer irons to hold the standards with the lower ends of these irons bent to engage over the flare boards, one set also bent to engage the sides, and bolts common to both the securing irons and standard 120 irons to secure the parts together.

8. In a wagon body, in combination with a bed, and sides for the same, a flare board, an iron for securing the same, said iron secured to the wagon side, a flaring portion 125

extending from said iron for mounting the flare board, and means for securing a top standard to the said parts comprising irons to engage such standard on two sides, said 5 irons being bent the one to lie along the flare board and the other to lie along the flaring portion of the flare board iron, for the purpose described.

9. In a wagon body, in combination with

a bed, sides and a flare board therefor, irons 10 secured to the sides, means on said irons for mounting the flare board, top standards, and irons for the top standards, and means whereby said flare board mounting means secures the standard irons removably along 15 the flare board.

JAMES MORRISON.
